(57) **CLAIM**

The ornamental design for a point of sale platform, as shown and described.

DESCRIPTION

FIG. 1 is a left side perspective view of a point of sale platform showing the new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is a left side perspective view of an alternate embodiment of a point of sale platform showing the new design;

FIG. 9 is a front view thereof; and,

FIG. 10 is a rear view thereof.

The broken lines showing the remainder of the point of sale platform are directed to environment. None of the broken lines form a part of the claimed design.
